Inventor

J. F. Etter

By Watson E. Colenair
Attorney

UNITED STATES PATENT OFFICE.

JOHN FRANK ETTER, OF CHAMBERSBURG, PENNSYLVANIA.

MOP.

Application filed January 14, 1922. Serial No. 529,388.

To all whom it may concern:

Be it known that I, JOHN FRANK ETTER, a citizen of the United States, residing at Chambersburg, in the county of Franklin 5 and State of Pennsylvania, have invented certain new and useful Improvements in Mops, of which the following is a specification, reference being had to the accompanying drawings.

- 10 This invention relates to certain improvements in mops and it is an object of the invention to provide a device of this general character having novel and improved means whereby the same can be readily and effectively employed without the necessity of the operator wringing the mopping cloth or rag with the hands or placing the hands within the bucket or other container employed in connection with the mop.
- 15 Another object of the invention is to provide a novel and improved device of this general character embodying a member or frame in which the mopping rag or cloth is adapted to be inserted and with which 20 is associated a head or plate carried by an operating handle whereby the rag or cloth after being saturated may readily have 25 squeezed therefrom excessive liquid.
- An additional object of the invention is to 30 provide a novel and improved device of this general character which, when inserted within a bucket or other receptacle containing liquid, may be operated in a manner to thoroughly cleanse the mopping cloth or rag 35 so that the cleansing operation may be materially facilitated.

The invention consists in the details of construction and in the combination and arrangement of the several parts of my improved 40 mop whereby certain important advantages are attained and the device rendered simpler, less expensive, and otherwise more convenient and advantageous for use, as will be hereinafter more fully set forth.

45 The novel features of my invention will hereinafter be definitely claimed.

In order that my invention may be the better understood, I will now proceed to describe the same with reference to the accompanying 50 drawings, wherein:

Figure 1 is a view in perspective illustrating a mop constructed in accordance with an

embodiment of my invention, the handle being shown in fragment;

Figure 2 is a transverse sectional view 55 taken through the device as illustrated in Figure 1;

Figure 3 is a view in perspective of the member or frame inverted.

As disclosed in the accompanying drawings, F denotes a member or frame rectangular in plan and which has its side members 1 relatively high. The upper marginal portions of a pair of opposed side members 1 are substantially defined by the inwardly 60 directed flanges 2. The flanges 2 are illustrated in the accompanying drawings as separate elements although it is to be understood that, if preferred, the same may be integrally formed with the side members 1. 70

The lower marginal portions of the remaining pair of opposed side members 1 are substantially defined by the outstanding flanges 3 and each of said flanges 3 adjacent its opposite ends has secured thereto the 75 cushions or feet 4 of suitable material and preferably of a yieldable material, such as a rubber composition. The lower face of the member or frame F has disposed thereacross the strands 5, said strands being wire 80 of desired gage with the extremities thereof secured in any preferred manner to the flanges 3.

P denotes a head or plate adapted to 85 snugly fit within the member or frame F and which may be readily inserted therein by inclining said plate on a desired angle so that the plate or head P may be applied within the member or frame F. When the head or plate P is in its normal position 90 within the member or frame F, the flanges 2 hold said head or plate against withdrawal therefrom.

Extending upwardly from the central portion of the head or plate P is a pair of 95 spaced wings 6 with which are pivotally engaged the shanks 7 extending outwardly from the lower end of the operating handle H. These shanks 7, as is particularly illustrated in Figures 1 and 2, are arranged in 100 divergence with respect to the handle member H and are also disposed on a desired angle or incline as may best comply with the requirements of practice. Secured to

the corner portions of the plate or head P, as indicated at 8, and underlying said head or plate are the blocks or pads 9 of suitable material but preferably of a rubber composition.

In practice, any suitable cloth or rag is applied within the member or frame F above the strands 5 whereupon the head or plate P is suitably arranged within said member 10 or frame F outwardly of or above the applied rag or cloth C. The handle member H is then suitably operated to submerge the assembled device within a bucket or other receptacle B diagrammatically indicated by 15 dotted lines in Figure 4.

After the floor or other surface has been operated upon by the cloth or rag C, the plate or head P may be removed from working coaction with the frame or member F 20 and engaged with a wiping cloth or rag positioned upon the floor or other surface to be cleansed and through the medium of the handle H, such floor or other surface may be readily and conveniently dried. The 25 gripping action of the plate or head P upon such wiping cloth or rag is materially facilitated by the blocks or pads 9 hereinbefore referred to.

After a cleansing operation has been effected through the instrumentality of the 30 mopping cloth or rag C, the assembled device will be again submerged within the washing liquid within the bucket or receptacle B and upon intermittently pressing down upon the cloth or rag C while in submergence, an action will be produced which will effect a thorough cleansing or rinsing of the rag or cloth C.

When the mop is in use, the pressure imposed upon the applied cloth or rag C by 40 the handle H through the medium of the head or plate P causes the cloth or rag C to extend outwardly between the strands 5 and to such an extent that the member or frame F does not come in contact with the floor or other surface to be worked upon so 45 that scratching or otherwise marring of such surface is substantially eliminated.

The cushions or feet 4 hereinbefore referred to are provided to afford additional 50 means to prevent the member or frame F from scratching or otherwise marring the surface being worked and particularly in the event if, for some reason, the cloth or rag C does not extend a sufficient distance 55 beyond the strands 5.

To facilitate the squeezing or rinsing of the cloth or rag C, the side members 1 of

the member or frame F are provided with suitable openings or perforations, as is 60 clearly shown in the accompanying drawings.

From the foregoing description it is thought to be obvious that a mop constructed in accordance with my invention is particularly well adapted for use by reason of the convenience and facility with which it may be assembled and operated, and it will also be obvious that my invention is susceptible of some change and modification without 70 departing from the principles and spirit thereof and for this reason I do not wish to be understood as limiting myself to the precise arrangement and formation of the several parts herein shown in carrying out 75 my invention in practice except as herein-after claimed.

I claim:

1. A mop comprising, in combination, a box-like structure having its top and bottom 80 faces open, a plate insertible within the structure through the top, and having free movement within the structure relative to the bottom face of the structure, spaced strands extending across the bottom open 85 face of the structure, and an operating member engaged with the plate, the walls of the structure being provided with openings.

2. A mop comprising, in combination, a box-like structure having its top and bottom 90 faces open, a plate insertible within the structure through the top, spaced strands extending across the bottom open face of the structure, and an operating member engaged with the plate, opposed walls of the structure having inwardly disposed flanges 95 beneath which the applied plate normally extends to hold the structure and plate against separation.

3. A mop comprising, in combination, a 100 box-like structure having its top and bottom faces open, a plate insertible within the structure through the top and having free movement within the structure relative to the bottom face of the structure, spaced 105 strands extending across the bottom open face of the structure, an operating member engaged with the plate, and a swabbing member insertible within the structure between the strands and the plate, pressure 110 upon the plate causing the swabbing member to project between the strands.

In testimony whereof I hereunto affix my signature.

JOHN FRANK ETTER.
